2,586,600

INTERLOCKED PRESSURE ROLLER AND
PAD ROLLERSten E. Bartelson, Ashland, N. J., assignor to
Radio Corporation of America, a corporation
of Delaware

Application September 7, 1946, Serial No. 695,500

4 Claims. (Cl. 271—2,3)

1

This invention relates to sound film advancing mechanisms, and particularly to an arrangement to insure the proper positioning of a pressure roller on the sound drum before the film is advanced. Although the invention is shown incorporated with a pressure roller on a sound film drum, it is to be understood that it may also be applied to one or more sprockets which are adapted to actually drive the film.

In Zimmerman U. S. Patent No. 2,219,731 of October 29, 1940, there is disclosed and claimed a toggle type of pad roller for a film advancing sprocket, the film being pulled by the sprocket over a drum. In such a drive mechanism, a pressure roller rests firmly against the surface of the film causing it to engage the supporting drum at all times. This pressure roller is a particularly important element for obtaining constant speed of the film past the light beam regardless of whether the light beam is a modulated recording beam or a constant intensity reproducing beam. If the driving mechanism is actuated with the pressure roller in the threading position; that is, spaced from the drum to permit threading of the film between the drum and roller, there is slippage between the film and the drum, thus inducing a variable speed to the film at the translation point. Furthermore, the film will separate from the surface of the roller causing the sound track to be out of focus. Thus, it is important that the pressure roller be in position at all times that the film is being advanced through the mechanism.

In threading a motion picture projector, pad rollers are used on the sprockets as disclosed in the above-identified patent. The operator, seldom if ever, fails to close the pad rollers, but frequently forgets to place the pressure roller in operative position against the film. To prevent this, the present invention provides means whereby the closing of the pad roller automatically closes the pressure roller. In this manner, whenever the film is threaded in a recorder or reproducer, there is no chance that the pressure roller will not be in its operative position when the driving mechanism is started.

The principal object of the invention, therefore, is to facilitate the operation of a film driving mechanism.

Another object of the invention is to provide an improved system of advancing film through a sound film reproducer or recorder.

A further object of the invention is to provide an improved pad roller and pressure roller actuating mechanism.

2

A still further object of the invention is to provide an interlocking pad roller and pressure roller combination whereby the closing of the pad roller automatically closes the pressure roller.

Although the novel features which are believed to be characteristic of this invention will be pointed out with particularity in the appended claims, the manner of its organization and the mode of its operation will be better understood by referring to the following description read in conjunction with the accompanying drawings, forming a part hereof, in which:

Fig. 1 is a side elevational view of a soundhead showing the pad roller-pressure roller actuating mechanism of the invention in operative position.

Fig. 2 is a side elevational view, similar to Fig. 1, showing the pad and pressure rollers in inoperative or threading position, and

Fig. 3 is an enlarged detail view of the pressure roller mounting.

Referring now to the drawings, in which the same numerals refer to like elements, the soundhead is constructed in general accordance with Loomis et al. U. S. Patent No. 2,019,147 of October 29, 1935, while it utilizes the pad roller invention disclosed in the above-mentioned Zimmerman patent. In a casing 10 is a sprocket 11 and a film drum 12 adapted to support a film 13 and carry it past the optical system 14 which directs a fine line of light thereupon from an exciter lamp 15. This light, after passing through the portion of the film overhanging the drum 12, is directed by a prism arrangement to a photocell housed within the shield 17. The sprocket 11 is driven from an appropriate source of power and pulls the film over the drum 12, which is provided with a viscous damper as disclosed in the above-mentioned Loomis et al. patent. From the sprocket 11, the film is pulled downwardly, passing out of the casing 10 through an aperture 18. Between the sprocket 11 and drum 12 is a filter arrangement composed of rollers 20 and 21 pivoted on an arm 22 mounted on a spring and dashpot mechanism 24.

The film is held on the sprocket 11 by the pad roller construction 26 shown in the above-identified Zimmerman patent, while the film is held on the drum 12 by a pressure roller 27 having a resilient tire 28. (See Fig. 3.) The roller 27 is mounted on an arm 30 pivoted at 31. Extending rearwardly from the pivot 31 is an arm 33 between which and an abutment 36 on the casing 10 is inserted a coil spring 34. A flexible shaft 38 from the pad roller 26 extends through a conduit 37 and through the coil spring 34 to the arm

33 of the pad roller 26 to which it is connected.

When the pad roller 26 and roller 27 are in closed or operative positions, shown in Fig. 1, the tension in the spring 34 causes the roller 27 to exert the proper pressure on the film 13. When the pad roller 26 is opened and held in its open position by the toggle spring 29, the roller is pulled away from the drum 12 by the shaft 38 in the conduit 37. Similarly, when the pad roller 26 is closed, the pressure roller 27 is brought 10 into contact with the film in operative position. With this arrangement, therefore, the possibility of not having the pressure roller in closed position on the drum 12 is eliminated when the pad roller 26 is closed. There is thus no opportunity 15 for the driving mechanism to be actuated without the proper arrangement of all driving elements of the advancing mechanism.

I claim:

1. A film drive mechanism comprising a 20 sprocket adapted to advance a film thereover, a drum adapted to have film pulled thereover by said sprocket and positioned at a distance from said sprocket, a pad roller adapted to maintain said film on said sprocket, a support for said pad roller, a pressure roller adapted to press said film against said drum at a predetermined pressure, a support for said pressure roller, a mounting for said support, means interconnecting said pad roller support and a part of said pressure 30 roller support to cause said pressure roller to ward and away from said drum when said pad roller is moved toward and away from said sprocket, respectively, and tensioning means through which said interconnecting means 35 passes, said tensioning means contacting a part of said mounting and said part of said pressure roller support to cause said pressure roller to exert said predetermined pressure on said film.

2. A film advancing mechanism in accordance with claim 1, in which said interconnecting means comprises a flexible shaft connected to said support for said pad roller and said part of said support for said pressure roller, and said tensioning means is a coil spring around said 40 45

interconnecting means between said part of said mounting and said part of said support for said pressure roller.

3. In a film advancing mechanism, a sprocket for advancing film thereover, a pad roller for holding film on said sprocket, an arm pivoted at one end and having said pad roller mounted on the other end thereof, a drum over which film is pulled by said sprocket, a pressure roller adapted to press said film on the surface of said drum, an arm pivoted at one end and having said pressure roller on the other end thereof, a second arm fixed to said first pressure roller arm, a shaft movable longitudinally and interconnecting the end of said last mentioned arm and said pad roller arm, movement of said pad roller toward said sprocket actuating said pressure roller toward said drum, a casing and tensioning means through which said shaft passes and which is positioned between the end of said last mentioned arm and a part of said casing.

4. A film advancing mechanism in accordance with claim 3, in which said shaft is flexible and said tensioning means is a coil spring for exerting a predetermined pressure of said pressure roller on said film when said pad roller is in operative position.

STEN E. BARTELSON.
